United States Patent Office

Des. 215,703
Patented Oct. 28, 1969

215,703

CAN

Fred Morgan, Blonay, Switzerland, assignor to Afico S.A.,
Lausanne, Switzerland, a Swiss company

Filed Aug. 15, 1968, Ser. No. 13,144

Term of patent 14 years

Int. Cl. D9—07

U.S. Cl. D9—240

FIG. 4

FIG. 3

FIG. 1

FIG. 2

FIG. 1 is an elevational view of a can showing my new design, with the slip cap removed;

FIG. 2 is an elevational view looking from the right of FIG. 1 with the cap in place;

FIG. 3 is an elevational view of the cap portion; and

FIG. 4 is a top plan view of the cap.

The sides opposite those seen in FIGS. 1 and 2 are the same in appearance as the respective sides shown.

I claim:

The ornamental design for a can, as shown and described.
